UNITED STATES PATENT OFFICE.

HARVEY REBER, OF HIGHWOOD, ILLINOIS, ASSIGNOR OF ONE-HALF TO GENEVIEVE GILLETTE, OF HIGHLAND PARK, ILLINOIS.

DESIGN FOR A COMBINED BOOK END AND CANDLESTICK.

61,328.

Specification for Design.

Patented Aug. 1, 1922.

Application filed July 7, 1921. Serial No. 483,060. Term of patent 3½ years.

To all whom it may concern:

Be it known that I, HARVEY REBER, a citizen of the United States, and resident of Highwood, in the county of Lake and State of Illinois, have invented a new, original, and ornamental Design for a Combined Book End and Candlestick (Case 1), of which the following is a specification, reference being had to the accompanying drawing, forming a part thereof, in which—

Figure 1 is a side elevational view of a combined book end and candlestick embodying my design,

Figure 2 is a top plan view of the same, Figure 3 is a front elevational view of the same.

I claim:

The ornamental design for a combined book end and candlestick as shown.

In witness whereof, I hereunto subscribe my name this 1st day of July, 1921.

HARVEY REBER.
